DESIGN FOR A SINK FIXTURE

Amy L. Thomssen and John M. Little,
Toledo, Ohio

Application October 9, 1946, Serial No. 133,852

Term of patent 14 years

(Cl. D91—3)

To all whom it may concern:

Be it known that we, Amy L. Thomssen and John M. Little, both citizens of the United States and both residing at Toledo, Lucas County, State of Ohio, have invented a new, original, and ornamental Design for Sink Fixture, of which the following is a specification, reference being had to the accompanying drawing, forming a part thereof, in which:

Figure 1 is a perspective view of a sink fixture showing our new and ornamental design;
Figure 2 is a top view of the design;
Figure 3 is an end view of the design; and
Figure 4 is a perspective view of the spray head.
We claim:

The ornamental design for a sink fixture, substantially as shown.

AMY L. THOMSSEN.
JOHN M. LITTLE.
